Arvid E. Anderson,

by Alexander S. Lunt.
His Attorney.

UNITED STATES PATENT OFFICE.

ARVID E. ANDERSON, OF SCOTIA, NEW YORK, ASSIGNOR TO GENERAL ELECTRIC COMPANY, A CORPORATION OF NEW YORK.

AUTOMATIC RECLOSED CIRCUIT-BREAKER SYSTEM.

Application filed September 8, 1924, Serial No. 736,447. Renewed June 13, 1927.

My invention relates to automatic reclosing circuit breaker systems and particularly to systems in which it is desirable to have the voltage of a circuit restored gradually 5 after the voltage has been reduced by the opening of a circuit breaker controlling the connection between a source of current and the circuit. My invention is of particular utility in connection with automatic reclosing systems for circuit breakers in certain 10 types of railway feeder circuits, where it is very essential that large and sudden changes in the trolley voltage shall not occur. For example in high voltage railway systems 15 which supply current to trains drawn by electric locomotives a large increase in the trolley voltage may increase the pull exerted by the locomotive so quickly that the train is pulled apart.

20 One object of my invention is to provide an improved automatic reclosing circuit breaker system of the type mentioned above whereby the voltage of the load circuit is increased gradually to its normal value after 25 the opening of a circuit breaker due to the occurrence of a predetermined abnormal condition on the load circuit controlled by the circuit breaker.

My invention will be better understood 30 from the following description when taken in connection with the accompanying drawing and its scope will be pointed out in the appended claims.

Referring to the drawing, 1 and 2 represent 35 conductors of two circuits which are adapted to be connected together by the circuit breakers 3 and 4 which may be of any suitable type. As shown in the drawing, the conductor 1 is one side of a direct current supply circuit and conductor 2 is one side 40 of a direct current load circuit. It is assumed that the ground is the other side of both circuits but it is to be understood, however, that my invention is not limited to a 45 system in which the ground is used as one side of the system.

5 represents a current limiting resistor which is connected so that it is short circuited by the circuit breaker 3, when the circuit breaker is closed, and is connected in 50 series between the supply and load circuits when the circuit breaker 4 is closed and the circuit breaker 3 is open.

It is desirable to use a resistor which is capable of dissipating for only a short time

the necessary energy consumed therein without becoming excessively heated because the cost and size of such a resistor are much less than one which is capable of dissipating continuously the necessary energy without 60 becoming excessively heated. Therefore, in order that such a resistor may be used satisfactorily it is necessary to provide a suitable switching arrangement whereby the resistor is not connected in series with the two 65 circuits, after the circuit breaker 3 has opened in response to an abnormal condition on the load circuit, until it is desirable to test the condition of the load circuit. In the arrangement shown, this result is accomplished by interlocking the two circuit breakers 3 and 4 so that whenever the circuit breaker 3 is opened in response to an abnormal load condition, the circuit breaker 4 is opened also to disconnect the two circuits 70 from each other. After the circuits have remained disconnected from each other for a sufficient length of time to allow the conditions on the load circuit to become stable, a time delay relay 6, which is energized in response to the opening of the circuit breakers 3 and 4, operates and effects the closing of the circuit breaker 4 to connect the resistor 5 in series with the two conductors 1 and 2. While I have shown the circuit breaker 4 as being in series with the circuit breaker 3 between the two conductors 1 and 2 it is evident that, if so desired, the circuit breaker 4 may be connected in the shunt circuit around the circuit breaker 4 which 80 includes the resistor 5.

As shown in the drawing, the circuit breakers 3 and 4 are of the type shown and claimed in the copending application Ser. No. 511,000 filed Oct. 28, 1921 by John F. 85 Tritle and assigned to the same assignee as this application. Each circuit breaker is held in its closed position by a holding coil 7 associated therewith and is opened when the current in a bucking bar 8, which is 90 connected so that it is energized in accordance with the current flowing in the circuit controlled by the respective circuit breaker, exceeds a predetermined value. In order that each circuit breaker may open in response 100 to one value of load current when the current through the bucking bar increases gradually and in response to a smaller value of load current when the current increases 105 rapidly, an inductance 9 is connected in 110

parallel with each bucking bar. For closing each circuit breaker a reset coil 10 and a resetting contactor 11 are provided therefor. The reset contactor and coil of each circuit breaker are connected and arranged so that the energization of the reset contactor 11 effect the energization of the reset coil 10, and the energization of the reset coil 10 moves the circuit breaker into its reset position in which position suitable auxiliary contacts are closed to effect the de-energization of the reset contactor. In the reset position of the circuit breaker the main contacts of the circuit breaker are not closed. The deenergization of the reset contactor effects the deenergization of the reset coil whereby the movable main contact of the circuit breaker is moved into engagement with the stationary main contact by a spring 12.

In order that the voltage across the load circuit may be increased gradually after the circuit breaker 4 closes, the current limiting effect of the current limiting means 5 is arranged to be varied in steps in response to the load connected to the load circuit. After the circuit breaker 4 is closed the portion 5^a of the resistor 5 is arranged to be short circuited by the contactor 14 when the voltage across the load circuit is sufficient to cause the relay 15 to close its contacts 16 which are in the circuit of the coil of the contactor 14. The voltage relay 15 has two voltage coils 17 and 18 both of which when energized tend to close the contact 16. The winding 17 is permanently connected between a point on the resistor 5 and ground so that it is energized in accordance with the voltage across the load circuit when the circuit breaker 4 is closed. The winding 18 is arranged to be connected across a suitable source of voltage by the relay 20 after the circuit breaker 4 is closed, the circuit of the coil 18 being arranged to be opened after the closing of the circuit breaker 3. The object in providing the relay 15 with two windings is so that the drop out value of the relay is higher than the pick up value. It will be observed that when both of the circuit breakers 3 and 4 are opened and the supply circuit is energized, substantially normal voltage remains impressed across the coil 17 since the resistance of the resistor 5 is very low compared with the resistance of the coil 17. Therefore, the relay 15 does not open its contacts 16 when the circuit breakers 3 and 4 open. When the circuit breaker 4 closes, the load, which is connected to the load circuit, is connected in parallel with the coil 17 so that the voltage across the coil 17 decreases to a low value. If the relay 15 had a pick up value higher than its drop out value, and the relay were adjusted so that it picked up and closed its contacts 16 when the load resistance was

above a predetermined value, the relay would maintain its contacts 16 closed after the circuit breaker 4 closed, if the abnormal load were not sufficient to lower the voltage below the drop out value of the relay. By having the relay adjusted, however, so that it will drop out in response to a higher voltage across the load circuit than the value required to pick up the relay a better calibration is maintained so that there is no chance for a premature closing of the contacts 16. In order that the relay 15 may have sufficient time to drop out after the closing of the circuit breaker 4, the time delay relay 21 is provided. This relay 21 controls the circuit of the relay 20 and is designed in any suitable manner so that it does not complete the circuit of the relay 20 until after the circuit breaker 4 has been closed for a certain length of time.

After the portion 5^a of the resistor 5 has been short circuited by the contactor 14, the portion 5^b is short circuited by means of a contactor 23, when the current through the portion of the resistor 5, which is not short circuited, decreases below a predetermined value. The circuit of the coil of the contactor 23 is controlled by a relay 24 having a winding 25 connected in parallel with the resistor 5 so that it is energized in accordance with the current flowing through the resistor from the supply circuit to the load circuit. Since the relay 24 is arranged to operate when the current decreases below a predetermined value and the coil 25 is short circuited under normal operating conditions it is necessary to provide suitable means for causing the relay 25 to open its contacts 26 when the circuit breaker 3 opens and to maintain its contacts 26 open independently of the current through the coil 25 until after the contactor 14 has short circuited the portion 5^a of the resistor 5. In order to accomplish this result the relay 24 is provided with a winding 27, the circuit of which is completed by a relay 28 as soon as the circuit breaker 3 opens. The winding 27 is arranged so that when it is energized, it opens the contacts 26 and maintains the contacts open independently of the amount of current through the coil 25. The circuit of the coil 27 is also controlled by the contactor 14 so that as soon as the portion 5^a of the resistor 5 has been short circuited the coil 27 is de-energized and the relay 24 is free to operate in response to the current through the resistor 5 to effect the closing of the coil circuit of the contactor 23.

After the portion 5^b of the resistor 5 has been short circuited, the circuit breaker 3 is arranged to be closed when the current through the portion of the resistor 5, remaining connected in series between the conductors 1 and 2, decreases below a predetermined value. This result is accomplished

by means of a relay 30, the contacts 31 of which are connected in the circuit of the coil of the reset contactor 11 of the circuit breaker 3. The relay 30 is provided with a winding 32 which is connected in parallel with the resistor 5 so that it is energized in accordance with the current flowing through the resistor from the supply circuit to the load circuit, and with a winding 33, the circuit of which is completed by the relay 28 as soon as the circuit breaker 3 opens so that the relay 30 opens its contacts 31 and maintains them open until after the contactor 23 closes. When the contactor 23 closes, the circuit of the coil 33 is opened so that the relay 30 is free to operate in response to the current through the resistor 5 to close the circuit breaker 3 when this current decreases below a predetermined value.

20 While I have shown means for short circuiting only two portions of the resistor 5 before the circuit breaker 3 is closed, in order to simplify the drawing, I do not desire to be limited to such an arrangement as it is evident that the number of steps in which the resistor 5 is short circuited may be made any desired number by merely adding additional relays similar to relay 33 and additional contactors similar to contactor 23, and having them interlocked in the manner shown so that they will operate in a predetermined sequence.

In order to protect the resistor 5 in case the temperature thereof becomes excessive, suitable temperature responsive devices such as thermostats 35 are placed near or on different portions of the resistor 5. These thermostats control the circuit of the relay 28 so that in case the temperature of any portion of the resistor becomes excessive, the relay 28 is deenergized and in a manner hereinafter described effects the opening of the circuit breaker 4 and renders the reclosing equipment inoperative until the over-heated portion of the resistor 5 has cooled.

The operation of the system shown is as follows: When the load conditions are normal and both of the circuit breakers 3 and 4 are closed, these circuit breakers are held in their closed positions by their respective holding coils 7. The circuit of the holding coil 7 of the circuit breaker 3 is from one side of a suitable source of current shown as a battery 39 through conductor 40, contacts 41 on the circuit breaker 4, conductor 42, holding coil 7 of the circuit breaker 3, conductor 43, resistor 44 to the ground which is connected to the other side of the battery. While I have shown the control circuit, supplied by the battery 39, as having one side grounded in order to simplify the drawing, it may be preferable in practice to use an ungrounded system. The circuit of the holding coil 7 of the circuit breaker 4 is from the battery 39 through the conductor

40, contacts 45 on the circuit breaker 3, conductor 46, holding coil 7 of circuit breaker 4, conductor 47, resistor 48 to ground. It will be observed that the circuit of each holding coil 7 is controlled by contacts on the other circuit breaker so that if one circuit breaker is opened, the other one is opened also.

When both of the circuit breakers 3 and 4 are closed, the other control devices are in the positions shown in the drawing. The contacts 16 of the relay 15 are closed since substantially normal voltage is impressed on the winding 17 thereof.

Upon the occurrence of a predetermined abnormal load condition the current through the bucking bar of one of the circuit breakers, depending upon the adjustments thereof, causes in a well known manner, the opening of the circuit breaker and the opening of this circuit breaker causes the opening of the other in the manner above described.

When the circuit breaker 3 opens the closing of its auxiliary contacts 49 complete a circuit from the battery 39 through the conductor 40, contacts 49, conductor 50, thermostats 35, coil of relay 28 to ground. The closing of the contacts 51 of the relay 28, when it is energized, connects the coils 27 and 33 of the relay 24 and 30 respectively across the battery 39 so that both of these relays open their respective contacts 26 and 31. The closing of the contacts 52, when relay 28 is energized, completes the circuit of the time delay relay 6 and the holding coil 7 of circuit breaker 4. This circuit is from the battery 39, through conductor 40, contacts 52, and conductor 46 which is connected to ground through two branches. One branch includes the holding coil 7 of the circuit breaker 4, conductor 47 and resistor 48 and the other branch includes the contacts 53 on the circuit breaker 4, conductor 54, and coil of time delay relay 6.

100 The energization of the holding coil 7 of the circuit breaker 4 does not effect the closing of the circuit breaker 4 since this can only be effected by the energization and the subsequent energization of the reset coil 10 while the holding coil 7 is energized.

110 After a predetermined time the time relay 6 closes its contacts 55 thereby completing a circuit in parallel with the resistor 48, for the reset contactor 11 of the circuit breaker 4. This circuit includes the coil of the reset contactor 11, conductor 56, contacts 55 of the time delay relay 6, conductor 57, contacts 58 of the contactor 14, conductor 59, contacts 60 on the circuit breaker 3 to ground. The completion of this circuit in parallel with the resistor 48 increases the current through the holding coil 7 which is desirable during the closing period. The closing of the contacts 61 of the reset contactor 11 connects the reset coil 10 of the

105

115

120

125

130

circuit breaker 4 across the battery 39 so that the circuit breaker 4 is moved into its reset position in which position the main contacts of the circuit breaker are not closed but the auxiliary contacts 53 are open and the auxiliary contacts 41, 62 and 63 are closed. The closing of the contacts 63 completes a short circuit around both the resistor 48 and the coil of the reset contactor 11 so that the energization of the holding coil 7 is further increased. The short circuiting of the reset contactor 11 causes this device to open its contacts 61, thereby effecting the deenergization of the reset coil 10, whereupon the spring 12 closes the main contacts of the circuit breaker 4 so that the resistor 5 is connected in series between the two conductors 1 and 2.

The opening of the auxiliary contacts 53 opens the circuit of the time delay relay 6 which returns to its normal position. The closing of the auxiliary contacts 41 completes the heretofore described circuit of the holding coil 7 of the circuit breaker 3. The closing of the auxiliary contacts 62 completes a circuit for the time delay relay 21 from the battery 39, through conductor 40 auxiliary contacts 49 on the circuit breaker 3, conductor 50, auxiliary contacts 62 on the circuit breaker 4, conductor 65, coil of time delay relay 21, to ground.

With a short circuit or an overload above a predetermined value connected across the load circuit, the voltage across the winding 17 decreases to such a low value, when the circuit breaker 4 closes, that the relay 15 opens its contacts 16. Therefore, when the relay 20 closes its contacts after the circuit breaker 4 has been closed a certain length of time, the circuit of the contactor 14 is not completed to short circuit the portion 5^a of the resistor until the voltage across the load circuit has increased to a predetermined value thereby indicating that the load has decreased below a predetermined value.

After a predetermined time, the time relay 21 closes its contacts 64 and completes a circuit in parallel with the coil thereof. This circuit extends from the conductor 65 through the contacts 64 of the relay 21, conductor 65', coil of relay 20 to ground. The closing of the contacts 66 of the relay 20 connects the coil 18 of the voltage relay 15 across the battery 39. The energization of the coil 18 alone is not sufficient to cause the relay 15 to close its contacts 16 but partially energizes the relay so that the relay operates in response to a lower voltage across the load circuit than if only the winding 17 were used.

As soon as the voltage across the load circuit reaches a predetermined value, after the operation of the relay 20, the relay 15 closes its contacts 16 and completes a circuit for the coil of the contactor 14 to short

circuit the portion 5^a of the resistor 5. This circuit is from the battery 39 through the conductor 40; contacts 66 of the relay 20, conductor 67, contacts 16 of the relay 15, conductor 68, coil of the contactor 14 to ground. The closing of contacts 69 of the contactor 14 also connects the conductors 67 and 68 directly together so that the contactor completes a locking circuit for itself. The opening of the contacts 58 removes the short circuit from around the resistor 48 so that the energization of the holding coil 7 is reduced to its normal value. The opening of the contacts 70 effects the deenergization of the coil 27 of the relay 24 so that the relay is free to close its contacts 26 in response to the current flowing through the portion of the resistor 5 which is not short circuited.

As soon as the load conditions become such, after the operation of the contactor 14, that the current through the resistor 5 permits the relay 24 to close its contacts 26, a circuit is completed for the coil of the contactor 23 so that the portion 5^b of the resistor 5 is short circuited. The circuit is from the battery 39, through the conductor 40, contacts 66 of the relay 20, conductor 67, contacts 26 of the relay 24, conductor 71, coil of contactor 23 to ground. The closing of the contacts 72 of the contactor 23 also connects together the conductors 67 and 71 so that the contactor 23 completes a locking circuit for itself. The opening of the contacts 73 of the contactor 23 opens the circuit of the coil 33 of the relay 30 so that the relay 30 is free to close its contacts 31 in response to the current flowing through the portion of the resistor 5 which is not short circuited.

As soon as the load conditions become such, after the operation of the contactor 23, that the current through the resistor permits the relay 33 to close its contacts 31, a circuit is completed in parallel with the resistor 44 for the reset contactor 11 of the circuit breaker 3. This parallel circuit extends from the conductor 43, through the coil of the reset contactor 11, conductor 74, contacts 31 of the relay 30, conductor 75, contacts 76 of the contactor 23 to ground. Since this circuit is in parallel with the resistor 44, the energization of the holding coil 7 of the circuit breaker 3 is increased during the resetting operation thereof. The closing of the contacts 77 of the reset contactor 11 connects the reset coil 10 of the circuit breaker 3 across the battery 39 so that the circuit breaker 3 is moved into its reset position, in which position the main contacts of the circuit breaker are not closed, but the auxiliary contacts 49 and 60 are open and the auxiliary contacts 45 and 78 are closed.

The closing of the auxiliary contacts 45

85

90

95

100

105

110

115

120

125

130

completes a circuit around the contacts 52 of the relay 28 so that the circuit of the holding coil 7 of the circuit breaker 4 is maintained closed after the relay 28 opens its contacts in response to the opening of the auxiliary contacts 49 of the circuit breaker 3. The opening of the contacts 60 prevents the short circuit around the resistor 48 being completed by the subsequent closing of the contacts 58 of the contactor 14 when this contactor is deenergized in a manner herein-after described.

The opening of the auxiliary contacts 49, in addition to effecting the deenergization of the relay 28, also effects the deenergization of the time relay 21 and the relay 20. In order to prevent the contacts 66 of the relay 20 from being opened, until after the closing operation of the circuit breaker 3 has been completed, any suitable means such as a dashpot may be provided for accomplishing this result.

The closing of the auxiliary contacts 78 connects the conductor 43 directly to ground through conductor 75 and contacts 76 of the contactor 23 so that the reset contactor 11 and the resistor 44 are short circuited and the excitation of the holding coil 7 of the circuit breaker is increased during the closing of the main contacts of the circuit breaker. The opening of the contacts 77 of the reset contactor 11 of the circuit breaker 3 deenergizes the reset coil 10 thereof so that the main contacts of the circuit breaker 3 are closed to connect the conductors 1 and 2 directly together.

When the relay 20 opens its contacts 66 after the closing of the circuit breaker 3, the contactors 14 and 23 open. The opening of the contacts 76 of the contactor 23 removes the short circuit around the resistor 44 so that the energization of the holding coil 7 of the circuit breaker is decreased but not enough to cause the circuit breaker 3 to open.

In case the temperature of any portion of the resistor 5 becomes excessive after the circuit breaker 4 closes, and before the resistor is short circuited by the circuit breaker 3, the circuit of the relay 28 is opened by one or more of the thermostats 35 associated with the resistor. The opening of the contacts 52 of the relay 28 opens the circuits of the time delay relay 6 and the holding coil 7 of the circuit breaker 4 so that this circuit breaker opens. The opening of this circuit breaker effects the opening of the coil circuits of the relays 21 and 20 and the contactors 14 and 23. The opening of the contacts 51 of the relay 28 opens the circuits of the coils 27 and 33 of the relays 24 and 30, respectively. Consequently, all of the control devices for the two circuit breakers are restored to their normal position so that neither of the circuit breakers can be re-closed automatically until the resistor has

cooled and the circuit of the relay 28 is completed.

While I have, in accordance with the provision of the patent statutes, shown and described my invention as applied to a particular system and as embodying various devices diagrammatically indicated, changes and modifications will be obvious to those skilled in the art, and I, therefore, aim in the appended claims to cover all such changes and modifications as fall within the true spirit and scope of my invention.

What I claim as new and desire to secure by Letters Patent of the United States is:—

1. In an automatic reclosing circuit breaker system, a supply circuit, a load circuit, a circuit breaker arranged to connect said circuits together, current limiting means arranged to be connected in series with said circuits when said circuit breaker is opened and to be short circuited by said circuit breaker when it is closed, means for opening said circuit breaker in response to a predetermined abnormal condition on said load circuit, means for decreasing the current limiting effect of said current limiting means when the load is less than a predetermined value after the opening of said circuit breaker, and means controlled by the current supplied through said current limiting means and operative only after the operation of said load responsive means for effecting the closing of said circuit breaker.

2. In an automatic reclosing circuit breaker system, a supply circuit, a load circuit, a circuit breaker arranged to connect said circuits together, current limiting means arranged to be connected in series with said circuits when said circuit breaker is opened and to be short circuited by said circuit breaker when it is closed, means for opening said circuit breaker in response to a predetermined abnormal condition on said load circuit, means responsive to the voltage across said load circuit for decreasing the current limiting effect of said current limiting means, and means responsive to the current flowing between said circuits through said current limiting means for subsequently effecting the closing of said circuit breaker.

3. In an automatic reclosing circuit breaker system, a supply circuit, a load circuit, a circuit breaker arranged to connect said circuits together, current limiting means arranged to be connected in series with said circuits when said circuit breaker is opened and to be short circuited by said circuit breaker when it is closed, means for opening said circuit breaker in response to a predetermined abnormal condition on said load circuit, means responsive to the voltage across said load circuit for short circuiting a portion of said current limiting means, and current responsive means operative

subsequent to the operation of said voltage responsive short circuiting means to short circuit another portion of said current limiting means and to effect the closing of said 5 circuit breaker in a predetermined sequence.

4. In an automatic reclosing circuit breaker system, a supply circuit, a load circuit, a circuit breaker arranged to connect said circuits directly together, current limiting means, means for opening said circuit breaker in response to a predetermined abnormal condition on said load circuit, means operative after said circuit breaker has been open for a predetermined length of time for 10 connecting said current limiting means in series between said circuits, means operative to short circuit a portion of said current limiting means when the load is less than a predetermined value after said current limiting means has been connected in series between said circuits for a predetermined length of time; and means controlled by the current through said current limiting means for short circuiting another portion 15 of said current limiting means and for effecting the closing of said circuit breaker in a predetermined sequence after said load responsive short circuiting means has operated.

5. In an automatic reclosing circuit breaker system, a supply circuit, a load circuit, current limiting means, a circuit breaker adapted to connect said current limiting means in series between said circuits, a second 20 circuit breaker adapted to short circuit said current limiting means, means for opening said second circuit breaker upon the occurrence of a predetermined abnormal condition of said load circuit, means responsive to the opening of said second circuit breaker for effecting the closing of said first-mentioned circuit breaker, means operative in 25 response to the voltage across said load circuit for short circuiting a portion of said current limiting means after the closing of said first mentioned circuit breaker, means controlled by the current through said current limiting means for short circuiting another portion of said current limiting 30 means after the operation of said voltage responsive short circuiting means, and means controlled by the current through said current limiting means for effecting the closing of said second circuit breaker after said other portion of said current limiting means has short circuited.

6. In combination, a supply circuit, a load circuit, a circuit breaker adapted to connect said circuits together, current limiting means arranged to be connected in series with said circuits when said circuit breaker is opened, means for short circuiting a portion of said current limiting means comprising an electroresponsive means having one winding connected across said load circuit and another

winding arranged to be energized after said circuit breaker opens, and means for short circuiting another portion of said current limiting means comprising an electroresponsive device having a winding arranged to be energized in response to the opening of said circuit breaker to move said electroresponsive device to its energized position and to be deenergized in response to the operation of said voltage responsive short circuiting means and a winding connected so as to be responsive to the current through said current limiting means.

7. In combination, a supply circuit, a load circuit connected to said supply circuit, means operative in response to a predetermined abnormal condition on said load circuit for effecting the disconnection of said load circuit from said supply circuit, a current limiting resistor, switching means for connecting said current limiting resistor in series with said circuits after said circuits have been disconnected from each other for a predetermined length of time, and means for short circuiting said resistor comprising a relay having a winding permanently connected to said supply circuit with said resistor in series therewith, and a second winding arranged to be energized after said resistor has been connected in series with said circuit for a predetermined length of time.

8. In combination, a supply circuit, a load circuit connected to said supply circuit, means operative in response to a predetermined abnormal condition on said load circuit for effecting the disconnection of said load circuit from said supply circuit, current limiting means, switching means for connecting said current limiting means in series with said circuits after said circuits have been disconnected from each other, and means for decreasing the current limiting effect of said current limiting means comprising a relay having a winding arranged to be connected across said load circuit by said switching means, and a second winding arranged to be energized after said switching means has been operated to connect said circuits together.

9. In combination, two electric circuits, current limiting means arranged to be connected in series with said circuits, and means for decreasing the current limiting effect of said current limiting means comprising a relay having a winding connected so as to be responsive to the current through said current limiting means and a second winding arranged to be energized until a predetermined condition occurs on one of said circuits after said current limiting means is connected in series with said circuits to prevent said relay from effecting the short circuiting of said current limiting means.

10. In combination, two electric circuits, a circuit breaker for connecting said circuits

together, current limiting means arranged to be connected in series with said circuits in response to the opening of said circuit breaker, and reclosing means for said circuit breaker comprising a relay having a winding connected so as to be responsive to the current through said current limiting means, and a second winding arranged to be energized in response to the opening of 5 said circuit breaker and before said current limiting means is connected in series with said circuits to prevent said relay from effecting the operation of said reclosing means, and to be deenergized in response to a predetermined condition on one of said circuits after said current limiting means has been connected 10 in series with said circuits. 75

11. In an automatic reclosing circuit breaker system, two electric circuits, a circuit breaker for connecting said circuits together, current limiting means, means operative in response to an abnormal condition on one of said circuits for effecting 15 the opening of said circuit breaker, means operative after said circuit breaker has been open for a predetermined length of time for connecting said current limiting means in series with said circuits, and means for controlling the reclosing of said circuit breaker comprising a relay having a winding arranged to be energized upon the opening of 20 said circuit breaker and to be deenergized after said current limiting means has been connected in series with said circuits and a second winding connected so as to be responsive to the current through said current 25 limiting means.

12. In an automatic reclosing circuit breaker system, two electric circuits, a circuit breaker for connecting said circuits together, circuit limiting means arranged to be connected in series with said circuits when said circuit breaker is opened, and means 40 for decreasing the current limiting effect of said current limiting means comprising a relay having a winding arranged to be energized in response to the opening of said circuit breaker and to be deenergized after 45 said current limiting means has been connected in series with said circuits, and a second winding connected so as to be responsive to the current through said current limiting means.

13. In combination, two electric circuits, a circuit breaker for connecting said circuits together, current limiting means arranged to be connected in series with said circuit in response to the opening of said 50 circuit breaker, and means for decreasing the current limiting effect of said current limiting means comprising a relay having a winding connected so as to be responsive to the current through said current limiting 55 means and a second winding arranged to be 60

energized in response to the opening of said circuit breaker and before said current limiting means is connected in series with said circuits to prevent said relay from effecting a decrease in the current limiting effect of 70 said current limiting means and to be deenergized in response to a predetermined condition on one of said circuits after said current limiting means has been connected in series with said circuits. 75

14. In combination, a supply circuit, a load circuit, a circuit breaker for connecting said circuits together, current limiting means arranged to be connected in series with said circuits when said circuit breaker 80 is opened, means operative in response to the voltage across said load circuit for short circuiting a portion of said current limiting means, and a relay for effecting the short circuiting of another portion of said current limiting means comprising a winding connected so as to be responsive to the current supplied from said supply circuit to said load circuit through said current limiting means and a second winding arranged 85 to be energized in response to the opening of said circuit breaker to prevent said relay from effecting the short circuiting of said other portion of said current limiting means and to be deenergized in response to the 90 operation of said voltage responsive short circuiting means to permit said relay to effect the short circuiting of said other portion of said current limiting means when the current through it is below a predetermined 95 value. 100

15. In combination, a supply circuit, a load circuit, a circuit breaker for connecting said circuits together, current limiting means arranged to be connected in series 105 with said circuits when said circuit breaker is opened, means operative in response to the voltage across said load circuit for decreasing the current limiting effect of said current limiting means, and reclosing means 110 for said circuit breaker comprising a relay having a winding connected so as to be responsive to the current supplied to said load circuit by said supply circuit through said current limiting means, and a second winding arranged to be energized when said circuit breaker opens to prevent said relay from 115 effecting the operation of said reclosing means and to be deenergized after the operation of said voltage responsive short circuiting means to permit said relay to effect the operation of said reclosing means when the current through said current limiting means is below a predetermined value. 120

16. In combination, a supply circuit, a load circuit, a circuit breaker for connecting said circuits together, current limiting means arranged to be connected in series with said circuits when said circuit breaker 125 is opened, means operative in response to the current through said current limiting means and a second winding arranged to be 130

the current through said current limiting means for decreasing the current limiting effect thereof, and reclosing means for said circuit breaker comprising a relay having a 5 winding connected so as to be responsive to the current supplied to said load circuit by said supply circuit through said current limiting means and a second winding arranged to be energized when said circuit 10 breaker opens to prevent said relay from

effecting the operation of said reclosing means and to be deenergized in response to the operation of said current responsive means to permit said relay to effect the operation of said reclosing means when the 15 current through said current limiting means is below a predetermined value.

In witness whereof, I have hereunto set my hand.

ARVID E. ANDERSON.
